EXPANDER AND APPLICATOR FOR PIPE PROTECTOR COLLARS

Joseph H. Goode, Houston, Tex.

Application November 15, 1948, Serial No. 60,087

2 Claims. (Cl. 29—236)

1
This invention relates to a protector collar expander and applicator and to the method of expanding a collar of resilient material, as rubber, and then fitting the expanded collar to firmly contract around a tubular element of lesser outer diameter than the inner diameter of the expanded collar.

It is an object of this invention to provide a protector collar expander and a method of expanding it in which the collar is expanded over a bucket assembly as the assembly is moved to force the collar against a stationarily held resilient pressure pad.

It is a further object of this invention to provide an applicator for removing the expanded collar from the bucket assembly to contract around a tubular element, as a stand of pipe, such applicator being of simple construction and comprising a minimum number of moving parts.

It is a further object of this invention to provide a protector collar expander and a means assembled therewith for operating the expander which means may also serve for operating the applicator.

It is a further object of this invention to provide a device of this class in which the bucket assembly with the expanded collar thereon may be readily positioned around the pipe which is to receive the collar.

It is still another object of this invention to provide a device of this class in which the means for operating the expander and for operating the applicator may be combined in a single unit.

Other and further objects of this invention will be obvious when the specification is considered in connection with the drawings, in which:

Fig. 1 is an elevation, part in section, showing the expander assembly prior to expanding a collar on to a bucket unit;

Fig. 2 is a side elevation, part in section, taken along line 2—2 of Fig. 1, which shows the expander unit after it has been operated to expand the collar;

Fig. 3 is a fragmentary plan view of a section of the expander showing the operating system therefor;

Fig. 4 is a sectional elevation of the applicator as it is being fitted over the tool joint at the end of a pipe stand;

Fig. 5 is an elevation of the applicator after it has been operated to force an expanded collar from sleeve to pipe;

Fig. 6 is a sectional elevation taken along line 6—6 of Fig. 5.

2
An expander assembly 1 comprises a frame 2, which has mounted at the top thereof the pressure pad 3; the bolts 4 passing through the walls of the cylindrical frame element 5 to hold the pressure pad 3 up against gravity. A mandrel 6 is threaded through the frame top 7 and through a stop plate 8, which is recessed in the pressure pad. Then the nut 9 is threaded on to the mandrel to firmly position it with relation to the frame. The mandrel 6 is sufficiently long to extend through the pressure pad and to receive thereon a protector collar 11, which in normal form is of sufficiently large diameter to slide over the mandrel with sufficient friction to maintain it thereon against gravity.

An assembly including a hydraulic cylinder 12, a piston rod 14 and a cup 21 is mounted on the frame base 13 in axial alignment with the mandrel axis. The cylinder has therein a piston rod 14 which extends above the cylinder to receive at the top thereof, the head 15. A bucket assembly 16, comprising the sleeve 17, the cone 18 fitted on top of the sleeve, and the base 19 which receives the sleeve 17, has an end portion 25 thereon which fits within the piston 14.

A cup 21, of a hard material having some resiliency, as neoprene, and which comprises the piston member of the piston assembly, is fitted on the lower end of the piston 14, and tightly against the inner-wall of the cylinder 12. The pipe line 22 extends from below the frame base 13 through the cylinder base 23 to communicate with the inner portion of the cup 21 and to operate the piston as will be hereinafter described.

This pipe line 22 extends to the valve 24 and through the line 25 to the vertical line 26 which has a pressure recording gauge 27 at the top thereof and which extends down as the discharge line 28 through which fluid from the pump 30 is discharged upwardly.

The re-circulating line 31 is hooked into the T 32 which operates the lines 26 and 28 and this re-circulating line leads back into the pump. The handle 33 operates a valve within the pump which opens and closes this re-circulating line.

From a T 35, intermediate the line 25, the line 36 branches off and has thereon the valve 37 to which is connected a flexible line 38 which leads to the applicator 44 to be hereinafter described. A prime mover 39, as a gasoline engine, is connected by means of coupling 40 to a speed reducer 41 and the crank 42 of this speed reducer is connected by a suitable system of linkages 43 to operate the pump 30.

When the operator is ready to expand a protector collar, he turns the handle 33 to close off the re-circulating passage 31, opens the valve 24, closes the valve 31, and starts the engine 39. This engine operates the pump through the speed reducer 41 to pump fluid into the piston 14, so that the force of this fluid acting on the cup 21 will move the piston upwardly so that the mandrel 6 will pass inside the cone 18 with the result that the top annular face 45 of the cone will come into contact with the end face 46 of the collar 11.

The resilient collar will first be forced back against the raised portion 48 of the pressure pad 3 and then as the pressure pad is further compressed, the collar 11 will begin to expand over the side face 49 of the cone. Further operation of the pump will force the raised portion 48 of the pressure pad 3 upwardly with the final result as shown in Fig. 2 that the cone becomes embedded within the pressure pad and the collar 11 becomes expanded upon the sleeve 16. The effect of dampening the impact of this operation, as by forcing one resilient material, the cone 11, against another resilient material, the pressure pad 3, is further abetted by the fact that the lightening holes 50 are provided in the pressure pad. The proportions of this pressure pad are such that by the time the cone 18 has been embedded therein at a desired distance, as shown in Fig. 2, the holes 50 have been completely closed as indicated by the lines 52, and the pressure pad sidewall 54 has been forced outwardly approximately in contact with the wall 5 of the frame element 4.

At this point, the operator turns the handle 33 to open the re-circulating line 31 and then the fluid within the cylinder 12 flows back therefrom as the weight of the bucket assembly 16 moves downwardly through gravity to force the piston 14 down to the bottom of its stroke. After this has happened, the valve 24 may be closed so that the pump 30 merely re-circulates fluid therethrough, or preferably the engine 39 may be stopped to shut off the machine.

When the bucket assembly 16, with the expanded collar thereon, has returned to lower position, it is an easy matter for the operator first to remove the cone 18 and then to lift the sleeve 17 off of the base 19 and position it over the tool joint 51 of a pipe stand 52, which is propped up by any conventional means, not shown. The sleeve may then be moved further along the pipe 52 to some preferred convenient distance near the tool joint at which it may be desired to apply a protector collar.

As shown in Fig. 4, the flexible line 38 may be connected, as by the union 56, to the end of a hollow piston 57 which has on the other end thereof a cup 58 of resilient material similar to the cup 21. In assembly, the cup end of the piston 57 is enclosed within the hydraulic cylinder 60 with the side of the cup in sliding contact with the inner wall thereof. The outer end of the piston 57 extends through the end 61 of the cylinder 60 and is threaded through the anchor plate 62 and affixed to the post 63 which terminates in the square section 64, adapted to be received at hole 65 of square cross section shown in Fig. 2 in the sleeve 11. The cylinder in turn, in assembly is threaded into the pusher plate 66 which is adapted to fit around the upper periphery of the turn down collar receiving portion 67 of the sleeve 11. The length of the sleeve portion 67 is sufficient to receive thereon the

collar 17 with sufficient length being left adjacent the shoulder portion 68 to receive the width of the pusher plate 66.

When the applicator 44 has been positioned on the sleeve 17, as shown in Fig. 4, and the sleeve and assembled applicator are at the position along the pipe 52 at which the collar 11 is to be installed, the valve 24 is closed and the valve 31 is opened so as to direct fluid through the flexible line 38 into the piston 57.

This results in fluid pressure being built up against the cup 58 to force the cylinder 60 forward so that the pusher plate 66 forces the collar 11 off of the sleeve portion 67 and immediately thereafter it tightly contracts around the pipe 52 upon the dis-establishment of contact between collar and sleeve.

It is herein pointed out that, whereas the drawing discloses apparatus adapted for expanding and then installing the collar on a pipe in sequence, this invention is not limited to such a sequence of steps, but it is also adapted for an assembly line operation whereby one collar may be expanded while another collar is being applied to a pipe. It is obvious that such may be accomplished by providing a plurality of sleeves 17 so that one sleeve, or a plurality of sleeves may be employed with an applicator, or plurality of applicators, on pipe while another sleeve is being employed in the bucket assembly 16 to have a collar expanded thereon. This arrangement may obviously be obtained by providing a pump 30 which is adapted, by any of several well known means, to operate an applicator or applicators, by a separate channel of flow or several separate channels of flow at the same time that another channel of flow from the same pump operates the piston 14 to expand a collar.

Broadly, this invention relates to a collar expander and applicator in which a bucket assembly is moved against a collar to force it against a stationarily held pressure pad to expand the collar onto the sleeve of the bucket assembly, and the invention also relates to an applicator which is simply constructed to force the expanded collar off of a sleeve from a bucket assembly by employing a minimum of moveable parts.

What is claimed is:

1. A protector collar expander comprising a base, a frame supported above said base, a resilient pressure pad supported in said frame, a mandrel on said frame and extending downwardly through said pressure pad and adapted to slidably receive an unexpanded protector collar thereon below said pressure pad, a cylinder mounted on said base and having a closed upper end with a bore therethrough, a piston in said cylinder and having a piston rod to extend through said bore, a head mounted on said rod and supported above said closed upper end when said piston is in its lowest position, said head having an annular ring portion for a sleeve adapted to be removably mounted on said head and adapted to fit said ring portion to center the sleeve coaxially with said rod, the upper end of said sleeve being adapted to have centered thereon an upwardly and inwardly tapered cone having a bore through the upper end of said cone to receive said mandrel therethrough, and means adapted to admit pressure fluid into said cylinder below said piston to elevate said rod, head, sleeve, and cone to press said cone against said collar and said collar against said pres-

sure pad and to force said collar over said cone and onto said sleeve as said cone bore extends around said mandrel, said pressure fluid means being also releasable to permit said piston to descend to position said cone below said mandrel whereby said cone may be removed from said sleeve, and said sleeve, with expanded collar thereon, may be lifted from said head.

2. A protector collar expander comprising a base, a frame supported above said base, a resilient pressure pad supported in said frame, a mandrel on said frame and extending downwardly through said pressure pad and adapted to slidably receive an unexpanded protector collar thereon below said pressure pad, a cylinder mounted on said base and having a closed upper end with a bore therethrough, a piston in said cylinder and having a piston rod to extend through said bore, a head mounted on said rod and supported above said closed upper end when said piston is in its lowest position, said head having an annular marginal portion for a sleeve adapted to be removably mounted on said head to fit said marginal portion to center said sleeve coaxially with said rod, the upper end of said sleeve being adapted to have removably centered

thereon an upwardly and inwardly tapered cone having a bore through the upper end of the cone to receive said mandrel therethrough and means adapted to admit pressure fluid into said cylinder below said piston to elevate said rod, head, sleeve and cone to press said cone against said collar and said collar against said pressure pad and force said collar over said cone and onto said sleeve as said cone bore extends around said mandrel.
